CLAIM

The ornamental design for a cat backpack with tunnel, as shown and described.

DESCRIPTION

FIG. 1 is a perspective view of a cat backpack with tunnel where the tunnel is in an expanded position, showing our new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a perspective view of the cat backpack with tunnel where the cat backpack with tunnel is in a closed state.

The “pecute” logo, shown in broken lines and forming no part of the claimed design, is a registered trademark of SHENZHEN HUAJIE ELECTRONIC COMMERCE CO., LTD.
